UNITED STATES PATENT OFFICE

2,077,192

EMERGENCY SPEED GOVERNOR

Donald F. Warner, Lynn, and Reginald G. Standerwick, Marblehead, Mass., assignors to General Electric Company, a corporation of New York

Original application August 20, 1931, Serial No. 558,339. Patent No. 2,020,977, dated November 12, 1935. Divided and this application May 11, 1935, Serial No. 21,052

2 Claims. (Cl. 200—80)

The present invention relates to emergency speed governors and has for its object an improved construction of such governors to permit adjustment during operation. This application is a division of our application, Serial No. 558,339, filed August 20, 1931 now Patent 2,020,977 November 12, 1935 on speed control mechanism. In said application we disclose a speed control mechanism for controlling and limiting the speed of a motor, which mechanism includes a speed controlling element, a speed limiting element and means for automatically adjusting one of the elements in response to adjustment of the other element. To make this clear, let us assume we have a motor provided with a speed-controlling element or speed governor setting the motor speed to 1000 R. P. M. and a speed-limiting element or emergency speed governor set to disconnect the motor or interrupt its operation as its speed reaches a maximum value, for instance, 1200 R. P. M. In our parent application we disclose means whereby a change of the setting of the speed-controlling element to 1300 R. P. M., for instance, causes automatically setting of the speed limiting element to operate at 1500 R. P. M.

A speed-limiting element or emergency speed governor of this kind must meet two requirements. It must be connectible to a speed-controlling element or speed governor and it must be adjustable during operation.

The single figure in the accompanying drawing shows an emergency speed governor in accordance with our invention. In this embodiment the speed governor is arranged to operate with a holding relay 16 which normally is energized to hold closed a switch 17 forming a part of a motor circuit (not shown). The relay 16 has a coil connected to an electric source 10 through the intermediary of the emergency governor. The latter is driven by a shaft 18 forming a part of a variable speed motor (not shown). As the speed of the motor reaches a certain maximum value, the governor interrupts the circuit for the energizing coil of the holding relay 16 which in turn permits the switch 17 to open by the action of a spring 11.

The emergency governor comprises a spindle 19 which is fixed in an opening in the end of the shaft 18 and is electrically insulated therefrom by a sleeve 20 of insulating material. The outer end of the spindle 19 forms a yoke or fork 21 between the arms or prongs of which is pivoted an eccentric emergency governor flyweight 22, the pivot being indicated at 23. The upper end of the flyweight 22 is the heavy end and is in the form of a contact arm 24. The weight 22 below the pivot

23 is provided with a conical bearing seat 25 with which engages a bearing cone 26 carried on one end of a tube 27. The other end of the tube 27 is slidably mounted in a washer 28 of insulating material held in a sleeve or cylinder 29. Located between the washer 28 and a flange on the tube 27 is a governor spring 30 which presses the bearing cone 26 against the seat 25. The sleeve 29 is slidably mounted in a slip ring or contact cylinder 31 formed integral with the yoke 21, that is electrically connected to the latter. Mounted on the slip ring 31 is a second slip ring or contact cylinder 32 insulated therefrom by an insulating sleeve 33. During operation, spindle 19, yoke 21, governor weight 22, tube 27, sleeve 29 and cylinders 31 and 32 rotate as a unit with the shaft 18. This rotating unit is located in a casing 34, the inner end of which is fastened to the end of a frame 35 of the drive motor. Mounted on the casing 34 are contact brushes 36 and 36a which engage slip rings 31 and 32 respectively. In the end of the sleeve 29 is a thrust bearing ball 37 with which engages a rod member 38. The latter is adjustable in axial direction of the motor shaft. It may be connected to a speed governor as described in our parent application. With a certain adjustment the rod 38 causes a definite compression of the governor spring 30.

The circuit for the operating coil of the relay 16 is formed through the brush 36a, the outer ring 32, the flyweight 24, the yoke 21, the inner ring 31 and the brush 36. The circuit is closed as long as the contact arm 24 of the flyweight engages the outer ring 32. As soon as the speed reaches a certain maximum value, the centrifugal force acting on the flyweight 22 causes outward movement of the contact arm against the force of the spring 30. The arms of the flyweight under such conditions are moved into a position indicated in dotted lines in the drawing, in which position the circuit for the relay 16 is interrupted causing movement of the switch 17 by the action of the spring 11. The speed at which interruption of the circuit takes place depends upon the compression of the spring 30, which compression may be regulated by axial movement of the normally stationary rod member 38.

Summarizing, the flyweight of our improved emergency speed governor normally closes an electric circuit through two ring members concentrically arranged with the spindle for the flyweight and rotatable therewith. The arrangement is simple in construction, reliable in operation and may be manufactured at small cost.

Having described the method of operation of

our invention, together with the apparatus which we now consider to represent the best embodiment thereof, we desire to have it understood that the apparatus shown is only illustrative and that the 5 invention may be carried out by other means.

What we claim as new and desire to secure by Letters Patent of the United States, is:—

1. An emergency speed governor comprising a rotatable spindle having an end portion forming 10 a yoke, a flyweight eccentrically pivoted on the yoke, a metal ring secured to the yoke and in conductive relation therewith, another metal ring insulated from the first ring and rotatable therewith, said other metal ring being normally in conductive 15 relation with the flyweight, a stationary casing, two brushes held on the casing, each brush engaging one of the rings, means for biasing the flyweight against the action of centrifugal force comprising a coil spring coaxially disposed within the inner ring, and means including a member supported on the stationary casing for adjusting 20 the spring during operation.

2. An emergency speed governor comprising a rotatable spindle having an end portion forming a yoke, a flyweight eccentrically held on the yoke, a metal ring secured to the yoke and in conductive relation therewith, another metal ring insulated 5 from the first ring and rotatable therewith, said other metal ring being normally in conductive relation with the flyweight, a stationary casing, two brushes held on the casing, each brush engaging one of the rings, means for biasing the flyweight against the action of centrifugal force comprising a spring coaxially disposed with the spindle, and means for adjusting the spring during 10 operation comprising a cylinder bearing against one end of the spring, a stationary member coaxial with the spindle and supported on the casing and a thrust ball intermediate the stationary member and said cylinder. 15
